UNITED STATES PATENT OFFICE.

GEORGE H. DORGELOH, OF SCHENECTADY, NEW YORK, ASSIGNOR TO GENERAL ELECTRIC COMPANY, A CORPORATION OF NEW YORK.

LIQUID RHEOSTAT.

1,233,852.

Specification of Letters Patent.

Patented July 17, 1917.

Application filed July 30, 1914. Serial No. 854,107.

To all whom it may concern:

Be it known that I, GEORGE H. DORGELOH, a citizen of the United States, residing at Schenectady, county of Schenectady, State 5 of New York, have invented certain new and useful Improvements in Liquid Rheostats, of which the following is a specification.

This invention relates to rheostats for controlling electric circuits, and especially to a form of liquid rheostat which will be found of peculiar advantage in the operation of induction motors having their rotor windings terminating in collector rings 15 which are to be connected to outside resistances. In this class of work it is desirable to have as great a range of resistance as possible between the starting and running positions of the rheostat and to reduce the 20 final resistance as low as possible in order to minimize the slip of the motor at full load.

One point of weakness in all liquid rheostats heretofore devised has been the low range of resistance, or, in other words, the 25 low ratio between the initial and the final resistance values. This defect has been due largely to the fact that the electrodes or plates must be spaced so far apart to avoid flashing over at high voltage that a low final 30 resistance could not be obtained.

My invention aims to overcome the difficulty by having in addition to the main electrodes a set of auxiliary electrodes which are more closely spaced than the main electrodes 35 and connected in parallel with the main electrodes but are not immersed until the resistance has been reduced. They are therefore out of circuit at starting and there is no danger of arcing due to the close 40 spacing. These auxiliary electrodes are separated from the liquid by a wall which may surround them so as to constitute a chamber which is separate from the main chamber. This prevents the vapor which rises from the 45 liquid before the auxiliary electrodes are immersed from coming into contact with the auxiliary electrodes and causing leakage or flash over between them. This auxiliary 50 chamber is connected with the main chamber so that the liquid will flow into it at the proper time and immerse the auxiliary

electrodes. With this arrangement there is a low final resistance due to closely spaced electrodes without danger of flashing over during the early stages of starting because 55 of the close spacing.

The accompanying drawing shows an embodiment of my invention, Figure 1 being a diagram of the electrical circuits, and Fig. 2 a diagrammatic section of the water tank 60 and its two electrode chambers.

The motor M to be controlled is an induction motor having its rotor windings connected to slip rings 1 which are connected by conductors 2 to a set of main electrodes or 65 plates 3 and a set of auxiliary electrodes 4 all inclosed in a tank R. The two sets of electrodes are separated by a wall or partition 8 which virtually forms a separate chamber for the auxiliary electrodes 4. The 70 two sets of plates are connected in multiple and those in chamber 5 are few in number and of large size, being long enough to dip below the lowest water level at all times. The plates 4 are more in number than the plates 75 3 and more closely spaced, and their lower ends are at a higher level than those of the plates 3, so that they hang well above the water at starting. The two chambers are connected by the orifice 7 in the 80 partition 8 which separates them, so that the water level is always the same in both chambers, and there is a free path for the electric current through the liquid from the plates in one chamber to those in the other. 85

In one end of the chambers is an opening, the height of whose sill 9 above the bottom of the chamber determines the depth of the liquid therein at starting. This opening is controlled by a gate or weir 10, preferably 90 carried on rock arms 11 pivoted at 12 and capable of oscillation by an arm 13, link 14, and pivoted lever 15. A sector gear 16 on the hub of the lever meshes with a pinion 17 on the shaft of a controller C. When the 95 lever is thrown over to turn on the current, it also lifts the weir, which causes a rise of the water level in the chambers 5 and 6.

A pump P driven by an electric motor M' takes liquid from the tank R and delivers it 100 constantly to the chambers 5, 6, the overflow running back into the tank, so that the

liquid is continuously circulated, and the heat is kept down.

5 Current is supplied to the three-phase motor M from leads a, b, c, two of which are controlled by contactors 18, 19, each provided with an interlock 20, 21 controlling the circuit of the other.

10 When the controller C is turned to the first forward position f and the switch S is closed, the winding of the contactor 18 will be energized by current flowing from the phase a through the contacts on the controller and the interlock 21 on the contactor 19, and back to phase b. This will close 15 the primary circuit of the motor M, and since there is some liquid in the bottom of the chamber 5 the secondary circuit will be completed through the high resistance afforded by the widely spaced long plates 3, and the motor will start. The steam or 20 vapor arising from the liquid will be prevented from coming into contact with the auxiliary electrodes and causing a leakage or flash over by the partition or wall 8. At 25 the same time that the controller is operated, the weir 10 will be lifted. The closing of the switch S also causes the motor M to start the pump P to forcing liquid into the water chambers. As the liquid rises 30 therein the resistance in the secondary circuit of the motor will decrease until the liquid reaches a height determined by the position of the upper edge of the weir, over which it then flows to the tank. For the 35 first position f of the controller, the weir stands at such a height that the liquid does not wet the auxiliary plates 4. But when the controller is thrown over to the position f', the weir is raised so high that the liquid immerses the plates 4, and since they are connected in parallel with the plates 3 and are set more closely together, the resistance is greatly lowered. When the water reaches 40 its highest level, the resistance is much lower 45 than it could be with the plates 3 alone. In like manner, if the controller is thrown to the opposite position r, the contactor 19 will be energized to reverse the motor, and in the final position r' of the controller the 50 plates 4 will be thrown in parallel with the plates 3 as before.

55 In the normal operation of my device, in controlling a collector ring induction motor for driving a hoist, for example, the switch S will be kept closed, so that the pump P will continuously circulate water between the tank R and the water chambers 5, 6. It is therefore only necessary to move the handle 15 in one direction or the other to effect 60 the starting of the motor either forward or backward. When the increasing speed of the motor has caused the voltage to drop sufficiently to permit a closer spacing of the plates, the handle is moved to the final posi-

tion to cause the liquid to immerse the plates 65 4. As the liquid rises, the resistance gradually lowers, until at the highest level of the liquid the final resistance is very low, the motor gets practically full line voltage, and the loss due to the slip of the rotor is 70 almost nil.

75 In accordance with the provisions of the patent statutes, I have described the principle of operation of my invention, together with the apparatus which I now consider to represent the best embodiment thereof; but I desire to have it understood that the apparatus shown is only illustrative, and that the invention can be carried out by other means.

80 What I claim as new and desire to secure by Letters Patent of the United States is:—

1. A liquid rheostat for electric circuits, comprising two connected chambers, two sets of electrodes in parallel with each other 85 one in each chamber, and means for immersing said sets successively.

2. A liquid rheostat for electric circuits, comprising two connected chambers, two sets of electrodes in parallel with each other 90 one in each chamber, those in one set depending to a lower level than the other set, and means for raising the level of the liquid in said chambers.

95 3. A liquid rheostat for electric circuits, comprising two connected chambers, a set of widely spaced electrodes in one chamber, a set of more closely spaced electrodes in the other chamber, and means for immersing said sets successively.

100 4. A liquid rheostat for electric circuits, comprising two connected chambers, a set of widely spaced electrodes in one chamber, a set of more closely spaced electrodes in the other chamber, the lower ends of the second set being at a higher level than those of the first set, and means for raising the level of the liquid in both chambers.

110 5. A liquid rheostat comprising a tank, main electrodes and auxiliary electrodes more closely spaced arranged to be successively immersed in said tank and means for preventing the vapor rising from the liquid when the main electrodes are immersed from coming into contact with the auxiliary electrodes.

115 6. A liquid rheostat for electric circuits comprising main electrodes, auxiliary electrodes more closely spaced than the main electrodes and normally connected in parallel therewith, a separating wall between the main and auxiliary electrodes, and means for immersing the auxiliary electrodes after the resistance has been reduced at the main electrodes.

120 7. A liquid rheostat for electric circuits comprising main electrodes, auxiliary electrodes more closely spaced than the main

electrodes and normally connected in parallel therewith, a wall for protecting the auxiliary electrodes from vapor generated at the main electrodes and means whereby
5 the auxiliary electrodes are immersed after the resistance has been reduced at the main electrodes.

In witness whereof, I have hereunto set my hand this 29th day of July, 1914.
